WOVEN FIBRE RUG

Ernest E. Lambert, Springfield, Mass., assignor to
Patchogue-Plymouth Mills Corporation, New
York, N. Y., a corporation of New York

Application January 4, 1946, Serial No. 639,070

11 Claims. (Cl. 139—420)

1

This invention relates to woven paper-fibre rugs and a new method of fabricating the same. It is particularly applicable to fibre rugs woven from colored paper threads.

Heretofore rugs have been woven from paper-fibre threads of various colors. The paper-fibre threads in turn have been formed from colored paper ribbons twisted together in a twisting machine to fashion the finished thread. These paper-fibre threads have been twisted either in one solid color or in a pencil stripe of two colors.

The use of paper-fibre threads in solid colors and in pencil stripes, necessarily limits the weaver's art in the fabrication of woven paper-fibre rugs to conventional patterns and optical effects, thus restricting the field of usefulness of the rugs and the resulting demand therefor in the trade.

One object of this invention is to enlarge the field of the weaver's art as applied to the optical effects and patterns which can be produced in rugs woven from paper-fibre.

Another object is an improved woven paper-fibre rug.

Another object is a paper-fibre rug woven with an improved construction of colored paper thread.

Another object is a paper-fibre rug of new and heretofore unconventional pattern.

Other objects will appear from the detailed description which follows:

In accordance with this invention, certain of the paper-fibre threads woven for example in the warp of the rug, are made from paper ribbons of different colors which are twisted into threads in such a manner that one colored paper ribbon forms an inner layer and another and differently colored paper ribbon forms the outer layer or covering of a substantial length of the paper-fibre thread, and thereafter the twist in the thread is modified to reverse the relative positions of the paper ribbons so that the ribbon which previously formed the covering becomes the inner layer and the paper ribbon which previously formed the inner layer becomes the outer layer or covering of the thread for a substantial length thereof. The resulting twisted paper-fibre thread accordingly has a covering, envelope or jacket, which alternates in color over substantial lengths thereof to produce a thread of variegated twist, sometimes referred to by those skilled in the art as a "jazz" thread. These variegated threads may be twisted in various color combinations and shadings as desired. The threads may be assembled in the warp as a group

2

or as a series of groups arranged according to their respective color combinations. In one suggested arrangement the threads may be staggered in the warp so that the body of the fibre rug when woven simulates the appearance of colored bands of threads of gradually varying width, forming light or dark areas of shading suggesting a soft overall mottled, heather, or moire textural effect.

10 In the drawings comprising two sheets of eight figures, numbered Figs. 1 to 8 inclusive, one suggested embodiment of the invention is illustrated.

Fig. 1 is a front view of a woven paper-fibre

15 rug reduced in size; (see figures and the drawings).

Fig. 2 is a front view of a fragment of the rug contained within the dotted lines 2—2 of Fig. 1, enlarged to approximately the actual size of the woven fabric;

20 Fig. 3 is a vertical cross sectional view taken along the line 3—3 of Fig. 2 looking in the direction of the arrows;

Fig. 4 is a longitudinal view partially broken away of one of the improved warp threads with 25 portions of the paper ribbons separated to show the construction of the twist;

Fig. 5 is a longitudinal view of a portion of a conventional striped thread;

Fig. 6 is a blown-up view of a section of the 30 thread of Fig. 4;

Fig. 7 is a transverse cross sectional view taken along the line 7—7 of Fig. 4 looking in the direction of the arrows; and

Fig. 8 is a transverse cross sectional view taken 35 along the line 8—8 of Fig. 6 looking in the direction of the arrows.

Like reference characters designate corresponding parts throughout the several figures of the drawings.

40 The fibre rug 10 (Fig. 1) is woven from paper-fibre threads of various colors. Paper-fibre threads made by twisting ribbons of "kraft" paper give good results. The rug 10 includes the usual warp threads 11—11 and the filling or 45 pick threads 12—12 (Figs. 2 and 3), woven to form a reversible fabric.

The paper-fibre threads forming the filling or pick 12 may be of any conventional type. They 50 may include paper-fibre threads made by twisting ribbons of colored paper together to form the uniformly striped thread shown in Fig. 5. The thread 12 (Fig. 5) includes at least two paper ribbons 16 and 17 of different colors, uniformly twisted together to form a spirally striped 55 thread. In Fig. 5 a white paper ribbon 16 and

a green paper ribbon 17 are twisted together to construct the striped paper fibre thread 12, which in this instance will be a green and white pencil stripe. Any other combination of colored ribbons 16 and 17 may be used.

The body of the woven fabric of the fibre rug 10 also includes my improved thread of variegated twist. This construction is illustrated in Figs. 4, 6, 7 and 8. One continuously twisted paper ribbon forms the stuffer or core 13. A plurality of other differently colored paper ribbons 14 and 15 are twisted around the stuffer in such a manner that one of the paper ribbons, for example the ribbon 14, constitutes the inner layer for a substantial length of the thread 11, and the other paper ribbon, for example the ribbon 15 constitutes the outer or covering layer of the thread 11 for the said length thereof. Throughout this length of the thread 11 the twisted inner ribbon 14 is entirely concealed by the twisted outer ribbon 15 which forms the outside jacket or covering of the thread 11. After the ribbons which form the thread 11 have been thus twisted for a substantial distance, the twist is modified to reverse the relative positions of the paper ribbons 14 and 15.

In the transitional step of the reversing operation a relatively short section of striped thread will be fabricated, as is best illustrated by way of example in the intermediate section of Fig. 4, which discloses each of the paper ribbons 14 and 15 spirally twisted around the stuffer 13 to produce a striped thread, the colors in the stripe (in this case red and brown), being determined by the colors of the paper ribbons 14 and 15. The length of the striped section will be determined by the speed of operation of the twist modifying mechanism of the twisting machine. By arresting the movement of the twist modifying mechanism of the twisting machine, at a predetermined intermediate point, the thread may be changed from a thread of variegated twist to a pencil stripe or other thread of uniform stripe. The stuffer 13 however, remains concealed beneath the twisted ribbons 14 and 15.

After the transition is completed the relative positions of the ribbons 14 and 15 are reversed. The twisted paper ribbon 15 now forms the inner layer and is completely hidden by the twisted paper ribbon 14 which now constitutes the outer layer or covering of the paper fibre thread 11. This section of the thread 11 presents the appearance of a twisted thread solid red in color.

The paper ribbons 14 and 15 which form the thread 11 may consist of a relatively unlimited variety of color combinations. The ribbons 14 and 15 may be of highly contrasting colors or they may be two shades of the same color, as for example, one ribbon may be a light shade and the other a dark shade, or one ribbon may be a bright shade and the other a pastel shade. In the specimen shown in Figs. 4, and 6 to 8 the paper ribbon 14 is indicated in red and the paper ribbon 15 in brown. As the stuffer 13 is entirely concealed by the paper ribbons 14 and 15, its color is unimportant.

The construction of the paper fibre thread 11 may perhaps be better understood from the blown-up view of Fig. 6 and the transverse cross sectional views of Figs. 7 and 8. In these views the paper ribbon 13 represents the stuffer or core of the fibre thread 11. It is covered by one of the twisted paper ribbons, which forms the inner layer. This inner layer is in turn covered by the other twisted paper ribbon which forms the outer or covering layer of the twisted fibre thread. In

Fig. 7 the paper ribbon 15 forms the inner layer, and the paper ribbon 14, the outer covering or envelope of the thread 11, while in Fig. 8 the relative positions of the ribbons 14 and 15 are reversed so that the twisted ribbon 14 now constitutes the inner layer and the twisted paper ribbon 15 the outer covering or envelope of the paper-fibre thread 11.

My variegated thread may be used by the weavers to produce many novel optical effects in reversible woven paper-fibre rugs. One of these novel effects is disclosed in the woven construction shown in Figs. 2 and 3. The variegated threads 11 are used in the warp of the rug 10, and are disposed in juxtaposition to form bands of different colors. These groups may if desired be separated by warp markers 18 which are merely variegated, or by other threads of distinctive coloring.

The threads may also be woven so that the color changes are staggered to produce bands of varying widths of color. In this arrangement the coloring of adjoining bands of warp threads tapers off to blend with the coloring of adjoining bands of warp threads which may be of a complementary coloring effect.

In a rug so woven the overall effect may be said to simulate in eye appearance, the moire effect in cloth, a mottled effect, or perhaps the grain in a piece of wood. The varying widths of the changing bands of coloring tapering off until they merge with one another produce a gradual changeover from the lighter to the darker shades and back again, so that the eye appearance of the changes in coloring is not sharp and distinct, but shades off softly, giving a sooth ing overall effect to the woven paper-fibres.

The fabric 10 is provided with a non-ravelling selavage edge 19 which is formed by looping back the filling or pick threads 12 at the edge of the fabric, thus producing a non-ravelling finished running edge.

The woven fabric is cut into suitable lengths according to the size of rug desired, and the ends are finished off in any suitable manner to prevent unravelling. One method of finishing off the top and bottom edges is shown in Figs. 2 and 3. A strip of binding material 20 of suitable width is folded over to cover the raw edge of the woven fabric. The binding material 20 is then secured to the marginal edge of the woven fabric by parallel lines of stitching 21 and 22 extending through the marginal edge of the woven fabric from front to back and traversing the surface of the fabric from one selvage edge 19 to the other (compare Figs. 2, 3 and 1).

What is claimed is:

1. A reversible woven rug fabric comprising paper-fibre threads, certain of said threads being fabricated out of distinctively colored complementary paper ribbons twisted to sub-divide the resulting thread into substantial lengths having the distinctive color of but one of said paper ribbons alternating with other substantial lengths having the distinctive color of said complementary paper ribbon, said ribbons as thus twisted forming a variegated thread, the said variegated threads being arranged side by side and woven in the same direction in the rug fabric, said threads being arranged with their adjoining lengths overlapping according to the color of the paper ribbon exposed in the length of thread to form overlapping bands having the color of only one of the said paper ribbons alternating with and overlapped by other bands having the color of the said complementary ribbon, and each

of said bands varying in width in accordance with the distinctive changes in color of said distinctively colored lengths.

2. A reversible rug fabric comprising paper-fibre threads, certain of said threads being fabricated out of a plurality of distinctively colored complementary paper ribbons so twisted as to sub-divide the resulting thread into substantial lengths having the distinctive color of but one of said paper ribbons separated by other substantial lengths having the distinctive color of said complementary paper ribbon, the said threads constituting the warp threads of the fabric, said warp threads being arranged in groups selected in accordance with the color of the paper ribbon exposed in the length of thread, the lengths of adjoining warp threads overlapping according to color to form bands having the color of one of the said paper ribbons alternating with other bands having the color of the said complementary ribbon, said overlapping bands extending across the rug from selavage edge to selavage edge thereof, and each of said bands varying in width in accordance with the progressive changes in color of successive warp threads of an arranged group.

3. A reversible rug fabric woven from paper-fibre threads, certain of said threads each containing at least three paper ribbons including a stuffer and a plurality of distinctively colored ribbons forming substantially concentric complementary layers enclosing said stuffer, each of the said ribbons alternately forming the distinctively colored outer layer of said thread thereby dividing successive portions thereof into distinctively colored lengths, the said threads being positioned side by side and woven in the same direction in the rug fabric, and said threads being woven in the fabric with their similarly colored lengths staggered so that each successive thread partially overlaps the distinctive coloring of its adjoining thread to produce bands of one distinctive color gradually changing into bands of another distinctive color thereby softening the impact of the changes in color tone to produce an overall woven textural effect.

4. A reversible rug fabric woven from paper-fibre threads, certain of said threads each containing at least three paper ribbons including a stuffer and a plurality of distinctively colored ribbons forming substantially concentric complementary layers enclosing said stuffer, each of the said ribbons alternately forming the distinctively colored outer layer of said thread thereby dividing successive portions thereof into distinctively colored lengths, and the said threads being arranged side by side as the warp of the fabric with their similarly colored outer layers staggered to partially overlap the distinctively colored outer layers of the adjoining warp threads to produce bands of one distinctive color gradually changing into bands of another distinctive color thus simulating a moire textural effect.

5. A reversible rug woven from paper-fibre threads, certain of said threads each containing at least three paper ribbons including a stuffer and a plurality of other distinctively colored ribbons forming substantially concentric complementary layers enclosing said stuffer, each of the said ribbons alternately forming the distinctively colored outer layer of said thread and dividing successive portions thereof into distinctively colored lengths, the said threads being positioned side by side and woven in the same direction in the rug fabric, said threads being woven with their similarly colored lengths staggered so that

each successive thread partially overlaps the distinctive coloring of the adjoining thread to produce bands of one distinctive color gradually changing into bands of another distinctive color thus simulating a moire textural effect, binding cloth folded over to enclose the raw edges of the rug fabric, and spaced parallel lines of stitches traversing both sides of the folded binding cloth and extending through the fabric of the rug from side edge to side edge thereof to form non-ravelling finished edges for the rug.

6. A reversible rug woven from paper-fibre threads, certain of said threads each containing at least three paper ribbons including a stuffer and a plurality of distinctively colored ribbons forming substantially concentric complementary layers substantially surrounding said stuffer, each of the said ribbons alternately forming the distinctively colored outer layer of said thread thereby dividing successive portions thereof into distinctively colored lengths, the said threads being positioned side by side as the warp of the fabric with their similarly colored outer layers staggered to partially overlap the distinctively colored outer layers of the adjoining warp threads to produce bands of one distinctive color gradually changing into bands of another distinctive color thus imparting a moire textural effect to the pattern of the rug, a plurality of strips of binding cloth, each of said strips being folded over to enclose one of the raw edges of the rug fabric, and lines of stitches traversing both plies of a folded strip of binding cloth and extending through both plies of the binding cloth and through the rug fabric from side edge to side edge thereof to form non-ravelling finished edges for the rug.

7. A reversible woven rug fabric comprising paper-fibre threads, certain of said threads being fabricated out of distinctively colored complementary paper ribbons twisted together to sub-divide the resulting thread into substantial lengths having the distinctive color of but one of said paper ribbons alternating with other substantial lengths having the distinctive color of said complementary paper ribbon, and said ribbons as thus twisted forming a variegated thread woven into the rug fabric as an integral part of the pattern.

8. A textile fabric comprising threads individually formed by twisting together a plurality of ribbons of differently colored paper in concentric layers, said ribbons alternating from the inner layer to the outer layer of each twisted thread and back again, to present substantial lengths of each ribbon in succession, and the resulting threads being woven into the body of the fabric as a constituent part of the pattern.

9. A reversible woven rug fabric comprising ribbons of differently colored paper, said ribbons being twisted together coaxially to form a thread having at least two concentric layers of different colors, substantial lengths of said ribbons alternating between the inner and the outer layers to fashion successive lengths of the thread in alternating colors, and the thread being selectively woven into the body of the rug fabric as an integral part of the pattern.

10. A textile fabric comprising paper ribbons of different colors twisted coaxially to use substantial lengths of each of said ribbons in succession as the covering ribbons of the coaxial threads thus formed, and said coaxial threads being selectively grouped in the fabric in accordance with the color changes of their covering ribbons to

form variegated woven bands which constitute a part of the fabric pattern.

11. A reversible rug fabric woven from paper-fibre threads, certain of said threads each containing a stuffer and a plurality of ribbons of 5 distinctively colored paper forming substantially concentric complementary layers enclosing said stuffer, each of the said ribbons alternately forming the outer layer of said thread thereby dividing successive portions thereof into distinctively 10 colored lengths, and the said threads being woven into the rug fabric as an integral part of the pattern.
